UNITED STATES PATENT OFFICE.

SAMUEL MARCUS, OF BROOKLYN, NEW YORK, ASSIGNOR, BY MESNE ASSIGNMENTS, TO
MARKON MANUFACTURING CO., INC., OF NEW YORK, N. Y., A CORPORATION OF
NEW YORK.

TONGUE AND TEETH FOR DOLL HEADS.

Application filed October 21, 1926. Serial No. 143,031.

This invention relates to dolls and like toys, and particularly to the tongue and teeth of such articles, and an object of the invention is to provide a tongue and teeth which may be readily assembled in position within the doll head and in which means is provided for insuring proper relative positioning of the tongue and teeth.

A further object is to so construct the tongue and teeth that they may be quickly and accurately placed in position within the doll head, and fastened, by relatively unskilled operators.

A further object is to so construct the tongue and the teeth that they may be assembled with each other and thereafter affixed within the doll head as a single entity.

A further and more detailed object is to provide the tongue and teeth so that one thereof shall include a tang disposed for engagement within a slot of the other to hold the two elements connected together for unitary handling and for insuring proper positioning of said elements relative to each other.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:

Fig. 1 is a vertical sectional view through a tongue and teeth constructed in accordance with this invention and showing the same as applied in position within a doll head, the portion of the doll head shown being likewise illustrated in vertical section.

Fig. 2 is a front elevational view of the tongue and teeth appearing in Fig. 1, the relative position of the mouth opening being shown by having dotted lines.

Fig. 3 is a view similar to Fig. 2 but illustrating a modified arrangement for holding the teeth and tongue assembled with each other, and

Fig. 4 is a view similar to Fig. 2 but showing a further modification in accordance with

which the tongue and teeth are formed from a single piece of material.

Referring to the drawings for describing in detail the structure illustrated therein the reference character L indicates the front portion of a doll head, the mouth opening being shown at 1.

The tongue, with which this invention is concerned, is indicated generally by the reference character H, and the teeth, with which this invention is also concerned, are indicated generally by the reference character G.

The tongue consists of a small piece of suitable material such as sheet celluloid or the like, preferably reddish in color, shaped to provide a main flat body portion 2 pressed outwardly at its centre to provide the tongue proper as 3 disposed to project forwardly through the opening 1 in simulation of the half protruding tongue of a small infant. At the upper margin of the base part 2 is a vertically extending portion 4 which is intended to lie substantially flat against the inner surface of the portion of the doll head intermediately above the mouth opening 1 and to be held fixed to the doll head by an appropriate cement or the like as 5.

The portion of the base 2 surrounding the tongue proper 3 bears against the inner surface of the doll head surrounding the mouth opening and, being of substantially the same color as the tongue proper, appears when viewed through the mouth opening, as the red interior of the child's mouth.

While the cement 5 may if desired be extended to rigidly connect the base 2 with the inner surface of the doll head and thus render the tongue proper immovable, it is preferable in most instances to fasten only the upper portion of the extension part 4 and thus leave the base 2 and the tongue proper 3 only resiliently held in position so that if the tongue proper be pressed by a child's finger during play said tongue proper will yield backwardly and thus add an element of interest for the amusement of the child.

It will be understood of course that such yielding movement of the tongue proper will be permitted by the natural springiness of the material, for instance celluloid, from which the tongue is made.

The teeth G may be made of any appropriate material but preferably consist of a small

piece of white sheet celluloid or the like. The main body of this piece of celluloid is shaped to provide two or more teeth proper as 6—6, and projecting upwardly therefrom is a central tang 7.

The extension part 4 of the tongue H is provided with an opening or slot 8 therethrough and the tang 7 is adapted to be introduced into said slot so that while the teeth proper 6—6 are exposed at the front surface of the base 2 of the tongue, just above the tongue proper 3, the tang 7 extends to and overlies the rear surface of the part 4 of the tongue so that it will be caught and held by the cement 5.

15 The relative sizes and dispositions of the tang 7 and slot 8 are such as to insure a proper positioning of the teeth with respect to the tongue and to hold said parts assembled particularly during the time while said parts 20 are being handled as an entity and placed into position within the doll head, and the cement 5 is being applied. An operator has merely to introduce the tang 7 into the slot 8, slide the bottom edge of the teeth backwardly along the upper surface 9 of the tongue proper 3, said surface at this time constituting a guide for the teeth acting as a cam to force the tang to a proper extent 25 through the slot 8, then place the assembled 30 tongue and teeth in position with the tongue proper extending into the mouth opening 1 of the doll head, and apply the cement 5 to thereafter permanently lock the tongue and teeth together and hold both connected 35 with the doll head.

The bottom edge of the teeth is preferably so formed as to provide a central notch-like formation thereon as at 10 and the surface 9 is slightly rounded so as to be highest at its central portion, and these configurations of the teeth and tongue provide a suitably definite guide co-operative between the tongue and teeth to keep the parts centered with respect to each other at all 40 times, particularly during the time while the teeth are being slid backwardly along the surface 9 for forcing the tang 7 into slot 8 and thereafter while the assembled structure 45 is being handled and attached within the doll head.

50 The structure suggested in Fig. 3 is similar to that already described except that in this instance the teeth member G is provided with a slot 11, and the extension part 55 4 of the tongue is provided with a tang as 12 adapted to extend through the slot 11 for holding the teeth assembled with the tang.

In utilizing this structure the teeth member is introduced over the tang 12 so that 60 said tang enters the slot 11 and the teeth member is then moved downwardly over the tang until the bottom edge of the teeth member engages against the upper surface 9 of the tongue proper 3. The notch 10 at the lower end of the teeth member is effective

here for centering the teeth member with respect to the tongue proper in the same manner as above set forth.

In Fig. 4 is illustrated a modification in which the tongue H and the teeth G are 70 formed from a single piece of material. The material employed may be the same as heretofore, namely sheet celluloid. The tongue part of the structure should be of reddish color however while the teeth part should 75 be white.

In making up the two parts from a single piece of sheet material the teeth part G is simply stamped out from the material of the tongue part along the opposite sides as 80 13 and 14, and the bottom edge as 15 of the teeth part, the upper side of the teeth part being left integral with the extension part 4 of the tongue, as at 16. In this way the teeth are allowed to project straight downwardly in an appropriate position while the base portion of the tongue part may be pressed backwardly by engagement with the inner surface of the doll head, and likewise 85 any backward movement of the base part 90 of the tongue, as by pressure from a child's finger as above referred to, will not move the teeth.

The relatively narrow portions as 17 and 18 at opposite sides of the teeth part G provide an area of weakness constituting a hinge connection between the portion of the device which is intended to be fixed to the doll head by the cement 5 and the base of the tongue which is intended to be capable of 100 backward flexing, and it is to be noted that similar areas of weakness, and consequent desirable hinge localities as 19 and 20 occur at opposite sides of the slot 8 in the structure Fig. 2 and at opposite sides of the tang 12 in Fig. 3, for permitting easy backward flexing of the tongues proper in said figures.

As many changes could be made in this construction without departing from the scope of the invention as defined in the following claims, it is intended that all matter contained in the above description or shown in the accompanying drawings, shall be interpreted as illustrative only and not in a limiting sense.

Having thus described my invention, what I claim as new and desire to secure by Letters Patent is:—

1. A tongue and teeth for doll heads, comprising tongue and teeth members one of said members having an opening therethrough and the other member having a part projecting through said opening in frictional contact with the wall thereof to hold said members assembled for handling as a single 120 entity.

2. A tongue and teeth for doll heads, comprising tongue and teeth members the tongue member having an opening therethrough and the teeth member having a part projecting 130

through said opening in frictional contact with the wall thereof for thereby connecting said members together for handling as a single entity.

5 3. A tongue and teeth for doll heads, comprising tongue and teeth members the tongue member having an opening therethrough and the teeth member having a part to project through said opening for thereby connecting

10 said members together for handling as a single entity, together with guide means to guide said members with respect to each other during the projection of said part of the teeth member through said opening.

15 4. A tongue and teeth for doll heads, comprising tongue and teeth members the tongue member comprising a base part having a tongue proper projecting therefrom, the base part having an opening therethrough spaced 20 from the tongue proper, and the teeth member having a main part arranged in the space between the tongue proper and the opening and having a tang projecting through said opening to hold the tongue and teeth members 25 assembled for handling as a single entity.

5. A tongue and teeth for doll heads, comprising tongue and teeth members the tongue member comprising a base part having a tongue proper projecting therefrom, the base 30 part having an opening therethrough spaced from the tongue proper, and the teeth member having a main part arranged in the space between the tongue proper and the opening and having a tang projecting through said 35 opening to hold the tongue and teeth members assembled for handling as a single entity, the tongue proper and the teeth member having parts co-operative to centre the teeth member with respect to the tongue proper.

40 6. A tongue and teeth for doll heads, comprising tongue and teeth members the tongue member comprising a base part having a tongue proper projecting therefrom, the teeth member being arranged upon said base part 45 in position adjacent the tongue proper, and said teeth and tongue members having co-

operative slot and tang parts to center the teeth member with respect to the tongue proper.

7. A tongue and teeth for doll heads, comprising tongue and teeth members the tongue member comprising a base part having a tongue proper projecting therefrom, the teeth member being arranged upon said base part in position adjacent the tongue proper, 50 and said teeth and tongue members having parts co-operative to center the teeth with respect to the tongue proper during the act of assembly and adapted to hold the teeth member assembled with the tongue member for 55 handling as a single entity.

8. A tongue and teeth for doll heads, said tongue comprising a base part having a tongue proper projecting therefrom, the base part having an opening therethrough, the 60 teeth having an extension projecting through said opening to hold the tongue and teeth assembled, the tongue having an extension by which it may be attached in position within a doll head, and said extension being of resilient material for the purpose described.

9. A tongue and teeth for doll heads, comprising a tongue and teeth members, the tongue member being formed of sheet material and comprising a base part having a 75 tongue proper pressed outwardly therefrom, the teeth member being arranged upon said base part in a position adjacent the tongue proper, and means connecting the teeth member with the tongue member to hold said 80 members assembled for handling as a single entity.

10. A tongue structure for doll heads, said tongue structure being formed from a single-piece of sheet material pressed to provide a tongue proper projecting from one 85 surface thereof, and said piece of material having a resilient extension therefrom adapted to serve as means by which to resiliently support the tongue proper within a doll head. 90

In testimony whereof I affix my signature,
SAMUEL MARCUS.
